UNITED STATES PATENT OFFICE.

DAVID C. GREEN, OF MILWAUKEE, WISCONSIN.

DESIGN FOR A GRATE-BAR.

SPECIFICATION forming part of Design No. 24,322, dated May 21, 1895.

Application filed January 14, 1895. Serial No. 534,918. Term of patent 14 years.

To all whom it may concern:

Be it known that I, DAVID C. GREEN, a citizen of the United States, residing at Milwaukee, in the county of Milwaukee and State of Wisconsin, have invented and produced a new and original Design for a Grate-Bar; and I do declare the following to be a full, clear, and exact description of the same, reference being had to the accompanying drawings, forming a part thereof, in which—

Figure 1 represents a perspective view of a grate-bar embodying my new design. Fig. 2 is a transverse sectional view on the line 2 2 of Fig. 1, and Fig. 3 is an end elevation.

My design relates to the new and original shape or configuration of the article.

The leading feature of this design for a grate bar comprises a series of disks of generally triangular external configuration, each presenting three flat faces connected by short slightly rounded surfaces, said disks being connected together by webs of metal whose ends are flush with the described faces of the disks, there being three of these webs between each two adjacent disks, the outer surface of each web being rounded, and the inner surface straight, so as to leave the portion of each disk external to the adjacent webs of the general shape of the frustum of a cone with rounded top or end and rounded base and the said conical projecting portions of the disks having slightly curved sides, of less diameter at said tops or ends than at said bases and there being a central longitudinal external row of spaces along each of the three flat faces of the grate bar, each of said external central spaces being in the form of a parallelogram.

A represents one of the generally triangular disks of the grate bar, and *aa a* the three flat faces thereof, while *b b b* represent the short slightly rounded connecting surfaces. These disks A are each further formed with a central circular perforation *c*, and each two adjacent disks are connected by three webs *d d d* having curved outer surfaces *e* and straight inner surfaces *f*, the ends *g* of said webs being flat and coinciding with the described flat faces of said disks. The exterior portions of the disks A beyond the said webs *d* are of less diameter at the ends *(b)* than at the line of said webs, being slightly curved on each side, as shown at *h h*. The end disks *A' A²* on their outer sides, are rounded with a shorter curve, as shown at *b' b'* than are the side surfaces *h h* of the intermediate disks. A trunion *B* of cylindrical form projects from the center of the end disk *A'* and a shaft *C*, also of cylindrical form, projects from the end disk *A²*. The end of this shaft is formed with polygonal flat faces, as shown at *D*, and said shaft is also fitted with a collar *E* of circular form, having a polygonal faced extension *F*.

What I claim is—
The design for a grate-bar substantially as shown and described.

In testimony whereof I affix my signature in presence of two witnesses.

DAVID C. GREEN.
